UNITED STATES PATENT OFFICE.

FREDERICK WILLIAM LEBERECHT, OF NEW YORK, N. Y.

SEWING-MACHINE ATTACHMENT.

1,382,098.

Specification of Letters Patent. Patented June 21, 1921.

Application filed March 17, 1920. Serial No. 366,467.

To all whom it may concern:

Be it known that I, FREDERICK WILLIAM LEBERECHT, a citizen of Germany, residing at New York, in the county of Bronx and 5 State of New York, have invented certain new and useful Improvements in Sewing-Machine Attachments, of which the following is a specification.

This invention relates to sewing machines 10 and has for its principal object to provide an attachment for stitching button holes which can easily and conveniently be applied to any form of existing sewing machines without requiring material changes 15 of the latter.

Another object is to produce an attachment which will be operated automatically from a reciprocating part of the sewing machine.

20 A still further object is to so construct the attachment that the same may be used either for stitching button holes or producing continuous zig-zag stitches.

And another object is to construct the attachment, so that the same may be utilized 25 for sewing on buttons or the like.

With these and other objects in view, my invention consists in the novel construction, combination and arrangement of parts as 30 will be hereinafter fully described and defined in the appended claims.

In the accompanying drawings in which similar reference characters denote corresponding parts, Figure 1 illustrates a side 35 elevation of a part of a sewing machine showing one mode of applying my attachment thereto; Fig. 2 is a top plan view of the button hole stitching attachment; Fig. 2^a is a cross section on line 2^a—2^a of Fig. 2; Fig. 3 is a side elevation thereof partly in 40 section; Fig. 4 is a cross section on line 4—4 of Fig. 3; Fig. 5 is a bottom view seen in the direction of arrows 5—5 of Fig. 3; Fig. 6 is a cross section on line 6—6 of Fig. 5; Fig. 45 7 shows the plain form of button hole stitching to be produced; Fig. 8 is a similar view as Fig. 3 of a somewhat modified construction; Fig. 9 is a top plan view of the swinging member as seen in direction of the 50 arrows 9—9 in Fig. 8; Fig. 10 is a vertical

section on line 10—10 of Fig. 8; Fig. 11 is a perspective view of the modified cam; Fig. 12 shows the second form of button hole to be produced by the modified construction; Fig. 13 is a plan view and Fig. 14 an elevation of the cutting mechanism.

Referring specifically to the drawing, my new attachment is so constructed that it can be easily and conveniently secured to any type of sewing machine, so as to be operated 60 automatically from the vertically reciprocating needle bar in the manner hereinafter fully explained.

The attachment comprises a frame 1 formed at one side with a projection 2 in 65 form of a plate whereby it can be attached to a bracket 3 fixed to the table T or the frame F of the machine.

The frame 1 at one end as at 2' has pivotally secured to it a bell crank lever 4 of which 70 one arm 4' is adapted to be connected to the vertically reciprocating needle bar B. This connection is effected by providing the arm 4' with an angular end portion 4^a having a longitudinal angular slot 4^b which engages 75 a lateral projection or the screw bolt S serving for fastening the needle N in the needle bar B.

The other arm 4^c of the bell crank has pivoted to it two levers 6 and 7 one above the 80 other, the object and function of which will be hereinafter fully described.

On a vertical spindle or pin 8 rotatively borne in the frame 1 at the end opposite to that carrying the bell crank 4 is rotatively 85 mounted a member 9 in a lateral extension 9' on which is provided a slot 9^c in which pivotally engages the lever 6 and whereby the reciprocating movement of the needle bar B and of the bell crank 4 will be transmitted 90 to the member 9 causing the latter to reciprocate horizontally on the spindle or pin 8. This member 9 has fulcrumed thereon at 10' a pawl 10 which is adapted to engage a horizontally disposed ratchet wheel 11 fixed 95 on the upper end of the spindle or pin 8 above the horizontally reciprocating member 9 and to impart to said wheel 11 a step by step motion. Secured to or formed integrally with the frame 1 is a segmental pro- 100

jection 12 to which is fixed a curved cam arm 13 adapted to actuate the pawl 10 during the upward movement of the needle bar so as to release said pawl from engagement 5 with the ratchet wheel 11. Carried by the segmental member 12 is an auxiliary pawl 14 serving to prevent retrograde movement of the ratchet wheel 10.

The pawl 10 is under the action of a 10 spring 15 which tends to hold it in engagement with the ratchet wheel 11 but which during the upward movement of the needle bar B is overcome by the action of the cam arm 13.

15 Mounted below the frame 1 and extending longitudinally thereof is the mechanism for feeding the goods on the table T in such relation to the vertically reciprocating needle N, as to produce a button hole stitch of 20 the form shown in Fig. 7 or of that shown in Fig. 12.

The mechanism for the two different forms of button holes somewhat varies, and I shall therefore describe the two mechanisms separately.

Referring first to the mechanism for the button hole form of Fig. 7, the same comprises a bar shaped member 16 which extends below the frame 1 and is capable of 30 executing short horizontal swinging movements. To this end, said bar is loosely mounted on a vertical spindle 17 rotatively borne in the frame 1. This spindle at its lower end carries a gear 18 adapted to be 35 constantly in meshing connection with a much smaller gear 19 fixed to the lower end of the spindle 8 which freely passes through a bore 16' made in the bar 16 so as not to interfere with the lateral swinging movement of the latter.

Above the wheel 18, the spindle 17 carries a cam 20. The bar 16 is grooved at 16² around the cam 20 so that when the spindle 17 is revolved as will be hereinafter explained, its cam 20 will coöperate with the walls of said groove 16² to impart to the said bar the desired lateral swinging movement.

Projecting from one end of the bar 16 toward the bell crank arm 4' is a bent arm 21 50 and hinged or otherwise pivotally attached to the same end of the bar is a short arm 22. To the free end of the short arm is removably fixed as by screws 23 or the like, a member 24 adapted to extend below the arm 21 longitudinally of the bar 16. This member which is adapted to take the place of the ordinary presser foot of a sewing machine carries a vertical pin 25 projecting through a slot in the arm 21. The upper end of said 60 pin has clamped or otherwise fixed to it a member 26 in which is tiltably borne a cam finger 27 serving for the manipulation of the presser plate or member 24 to bring the latter into contact with the fabric located on 65 the table T, and in which button hole

stitches are to be produced. Between the arm 21 and the tilttable presser plate 24, I provide a spring 27' wound around the pin 25 and which has the tendency to normally press the plate 24 into contact with the fabric. On tilting the cam finger the pin 25 will be moved upwardly lifting the plate 24 from the goods against the pressure of the spring. In the plate 24, I provide a longitudinal recess 24' through which the needle 70 N is allowed to pass in and out of the fabric during its vertical reciprocating movement. Slidably engaging the longitudinal edges of the plate 24 is a member 28. This member carries a gripping member 29 the bottom 80 edges 29' of which are toothed or roughened and which serves to grip the fabric when the member 24 is in its depressed position. This member 29 is preferably made in the form of a rectangular frame extending longitudinally of the member 24 and is centrally pivoted as at 29² to the slide 28 so as to tilt horizontally in order that it may adjust itself according to the thickness of the fabric to be treated.

90 The slide 28 carrying the gripping member 29 is adapted to be operated automatically by the reciprocating needle bar through the medium of an arm 30 one end of which is pivotally connected to the slide 95 at 30' and the other, to a crank pin 31 fixed to and projecting from the lower face of the large gear 18. The stroke of the slide 28 adapted to conform with the length of the button hole can be adjusted. To this end, I 100 provide a slot 18' in the bottom of the gear 18 along which the crank pin 31 can be displaced according to the adjustment required.

During the operation of the needle bar B the bell crank 4 will swing vertically and 105 through the medium of the lever arm 6 swing the pawl 10 around the axis of the spindle 8. In consequence thereof the ratchet 11 will be fed step by step imparting rotary motion to the pin 8 and consequently to the 110 small gear 19 which in turn will revolve the larger gear 18. The latter will cause the spindle 17 to revolve, which by its cam 20 will operate the bar 16 to swing it laterally from the central or normal position. In 115 consequence thereof, the gripping member 29 engaging the fabric will first shift the latter to one side relative to the needle. Thereupon through the medium of the crank pin 31 and arm 30 the gripping member 29 120 will be longitudinally moved a distance corresponding to the length of the button hole. Then the cam 20 again will operate the bar 16 to cause the gripping member 29 in a 125 similar manner as before to shift the fabric laterally relative to the needle N in the direction opposite to that of the first lateral movement. Then again, through the medium of the crank pin 31 and arm 30 the gripping member 29 will shift the fabric 130

longitudinally in a direction opposite to the first longitudinal movement completing the button hole stitching operation around the edges of the button hole which may have 5 been previously cut in the fabric.

The stitches made around the edges of the button hole are as usually zig-zag stitches. The latter are effected by the following mechanism:

10 The free end of the bar 16 is provided with a longitudinal slot 16^a. Adjustably borne in said slot is a pin 32 which projects vertically upward. Rotatively mounted in the frame 1 above said pin is a horizontally 15 disposed spindle 33 on which is mounted a wheel 34 provided in its circumference with an annular cam groove 34' in which engages the free end of the pin 32. The cam groove as will be clearly seen from Fig. 4 20 is of zig-zag shape so that as the cam revolves the pin 32 will be moved alternately to one side of its normal central position to the opposite side thereof, and transmit this zig-zag motion to the bar 16, and consequently 25 to the presser plate 24 and gripping member 29, whereby the fabric apart from and simultaneously with the movement imparted to it through the medium of the cam 20 and crank pin 31 will be given a lateral 30 oscillatory motion. The plate 24 will therefore receive a composite movement, to wit, swinging around the pin 32 to move the fabric according to the width of the button hole and simultaneously swinging in zig-zag 35 fashion around the spindle 17 to produce a zig-zag stitch.

The zig-zag groove 34' has flattened portions (Fig. 4) which are adapted to hold the pin 32 stationary for the short periods 40 of time during which the needle is carrying out its upward strokes.

The cam 34 receives its rotary motion through the medium of a ratchet 35 made integral therewith or fixed thereto, and a 45 spring actuated pawl 36 fulcrumed to an arm 37, the free end of which is slotted as at 37' to be slidably guided on the spindle 33. The other end of said arm 37 is connected by a pin 38 to the aforesigned arm 50 7 connected to the bell crank lever arm 4^a. Thus the vertical swinging movement of the bell crank 4 while causing the movement of the bar 16 and of the gripping member 29 in the afore-described manner 55 will simultaneously impart a rotary step by step movement to the cam 34 as a result of which the pin 32 will impart the zig-zag motion to the bar 16.

To produce button hole stitches for button 60 holes of the shape shown in Fig. 12, the bar 16 and cam 20 must be somewhat modified. This modification is shown in Figs. 8, 9, 10 and 11.

The cam 39 is substantially of the construction shown in Fig. 11 *i. e.* composed of

a plurality of cam surfaces such as 39', 39^a and 39^b and is mounted in a correspondingly shaped groove 40' of the modified bar 40.

The groove 40' and the composite cam 39 are so shaped that the presser plate 24 carried by the member 40 will first be swung by one of the cam surfaces as 39' to one side of its normal positions to produce the part *a* of the button hole. Then the slide or gripping member 29 will be longitudinally displaced through the medium of the crank pin 31 and arm 30. Thereupon another cam surface as 39^a will swing the member 40 farther out in the same direction to produce part *b* of the eye portion of the 80 button hole. The third cam surface as 39^b in conjunction with the lateral displacement of the gripping member will cause the member 40 to describe the semi-circular edge *c* of the eye portion of the button hole. The gripping member 29 will then move longitudinally in opposite direction to the first longitudinal motion and cam 39' will cause the member 40 to move so as to produce the edge *e* of the button hole.

When applying the button hole stitching attachment to a sewing machine the ordinary fabric feeder and presser foot are removed.

My attachment may be utilized also for 95 other purposes than producing button hole stitches. Thus it may be used for producing continuous zig-zag stitches, or for sewing on buttons having eyes.

The mechanism for cutting or punching 100 out the button hole is shown in Figs. 13 and 14. A knife 55 may be suspended from the arm 21 to be automatically operated by the bell crank arm 4'. To this end an arm 56 may be fulcrumed to the free end of the 105 arm 21 to swing horizontally and hinged or otherwise pivotally attached to said arm may be a second arm 57 capable of swinging vertically. This arm 57 is normally held in raised position by a spring 58 attached to the arm 56. Projecting laterally from said arm 57 is a pin 59 adapted to extend into the path of the lever 4' when it is desired to operate the knife 55. The latter which may be in form of a blade or 110 punch is fixed to the arm 57 and adapted to project downwardly therefrom toward the slot 24' in the presser plate 24. When it is desired to punch out or cut the button 115 hole the arm 56 is turned on its fulcrum until the pin 59 projects below the arm 4', so that when the needle bar B descends the arm 4' will strike said pin and depress the lever 57 carrying the blade 55.

When not in use the knife is turned side- 125 wise so that the pin 59 will be out of the way of the reciprocating lever arm 4'.

What I claim and desire to secure by Letters Patent is:

1. In combination with a sewing machine,

an attachment for stitching button holes, comprising a cam controlled horizontally swinging presser plate a longitudinally 5 slidable gripping member on said presser plate, and a common means for transmitting motion to said cam and gripping member from a reciprocating part of said machine.

2. In combination with a sewing machine, an attachment for stitching button holes, 10 comprising a cam controlled horizontally swinging member, a vertically tilttable presser plate carried by said member, a longitudinally slidable gripping member on said presser plate and a common means to transmit 15 motion to said cam and slidable gripping member.

3. In combination with a sewing machine, an attachment for stitching button holes, comprising a horizontally swinging presser 20 plate a longitudinally slidable gripping member on said plate, a cam for swinging said presser plate laterally according to the configuration of the button hole, a cam for simultaneously imparting a lateral oscillatory movement to said presser plate and common means for transmitting movement 25 of a reciprocating part of the sewing machine to said sliding member and to both said cams.

30 4. In combination with a sewing machine, an attachment for stitching button holes, comprising a frame, a horizontally swinging grooved member mounted therein, a vertically tilttable presser plate carried by said member, a cam mounted in the groove of 35 said member to move the latter laterally according to the configuration of the but-

ton hole, a second rotary cam carried by said frame and serving to reciprocate the said member horizontally, a gripping member slidably supported on said presser plate and means operated from the needle bar and including a bell crank to impart movements to said cams and gripping member. 40

5. In combination with a sewing machine, 45 a button hole cutting and stitching attachment, comprising a frame, a horizontally swinging slotted presser plate, carried by said frame, a vertically movable arm operated from the needle bar and transmitting 50 motion to said presser plate and a vertically movable cutting member carried by said frame so as to swing horizontally with said presser plate and operated from said arm. 55

6. In combination with a sewing machine, a button hole cutting and stitching attachment, comprising a frame fixed to said machine, a horizontally swinging presser plate carried by said frame, a movable arm operatively connected to a reciprocating part of said machine, and adapted to transmit motion to said presser plate, a vertically movable cutting member carried by said frame to swing horizontally together with said 60 presser plate and means whereby said cutting member in a certain position will be actuated by said arm. 65

In testimony whereof I affix my signature in presence of two witnesses.

FREDERICK WILLIAM LEBERECHT.
